UNITED STATES PATENT OFFICE

2,530,054

LIQUID SEPARATOR

Arthur Gordon, Chicago, Ill.

Application December 4, 1946, Serial No. 714,043

6 Claims. (Cl. 210—43)

1

This invention relates to the separation of liquids, and especially to the separation of the lightest liquid from a mixture of liquids of different specific gravities.

The separating system of this invention is simple and easy to manufacture and does not employ any moving parts. It was adapted to readily separate and remove the lightest liquid from a mixture of liquids having different specific gravities regardless of the rate of flow thereof or the percentage of the lightest liquid. A specific example of an installation in which the invention is of particular importance is that of separating the oil from a mixture of water and oil. The invention provides ready and continuous separation and will handle large volumes of liquids.

The invention will be described as related to the embodiments of the same set out in the accompanying drawings. Of the drawings, Fig. 1 is a vertical section taken longitudinally through one embodiment of the invention along line 1—1 of Fig. 2; Fig. 2 is a horizontal section taken along line 2—2 of Fig. 1; Fig. 3 is a vertical section taken along line 3—3 of Fig. 2; Fig. 4 is a vertical section taken along line 4—4 of Fig. 2; Fig. 5 is a vertical section taken along line 5—5 of Fig. 1 and Fig. 2; and Fig. 6 is a longitudinal vertical section taken through a second embodiment of the invention.

While the invention is susceptible of various modifications and alternative constructions, it is shown in the drawings and will hereinafter be described in the preferred embodiments. It is not intended, however, that the invention is to be limited thereby to the specific construction disclosed, but it is intended to cover all modifications and alternative constructions falling within the spirit and scope of the invention as defined in the appended claims.

The embodiment shown in Figs. 1 to 5 inclusive comprises a main body portion 10 having a front wall 11, a rear wall 12, and side walls 13 and 14. The main body portion 10 is open at the top and provided with a removable cover member 15. The interior of the unit is divided into an inlet compartment 16, an intermediate compartment 17, and an outlet compartment 18. The compartments are divided from each other by a pair of vertical T-shaped wall members 19 and 20. The wall member 19 is preferably formed integrally with the rear wall 12, while the other wall member 20 is likewise formed integrally with the front wall 11. These wall members 19 and 20 have their main portions in substantially the same plane which bisects the main body portion 10. The tops

2

21 and 22 of the T-shaped members 19 and 20 are substantially parallel to each other and separated from each other. The flat portion 21 is provided with end flanges 23 and 24 and the flat portion 22 is provided with similar flanges 25 and 26. Flanges 23 and 25 extend toward each other and are substantially co-planar; likewise, flanges 24 and 26 extend toward each other and are substantially co-planar. The T-members 19 and 20 terminate at their lower ends short of the bottom 27 of the body portion 10. A separator 28 is provided having side walls 29 formed as a basket and adapted to be held between flat portions 21 and 22 and flanges 23, 24, 25, and 26. The separator 28 is adapted to be slid in a vertical direction into place between the flanges and may be removed through an auxiliary cover 30 in the cover member 15. One vertical wall 29 which separates the intermediate chamber 17 from the outlet chamber 18 is provided with a plurality of spaced apertures 31. An inverted V-shaped screen 32 is provided between the side walls 29 of the separator 28. This screen is removable and is provided at its topmost portion with a handle 33. As can be seen from Fig. 3, a horizontal flange 34 is provided extending between the bottoms of flanges 25 and 26. A similar flange 35 is provided between side flanges 23 and 24. These two horizontal flanges hold the separator in place.

An inlet connection 36 communicates with the inlet chamber 16 through the end wall 14 (Fig. 3). A vertical baffle wall 37 is provided within the inlet chamber 16 spaced from the end wall 14 and extends from near the top of the unit downwardly to a point short of the bottom 27. An outlet pipe 38 is provided communicating at its inner end with the outlet compartment 18. The communication is provided for by having the inner end of the outlet pipe 38 attached to a passageway 39 extending down along the side of the main body portion 10 and communicating with a horizontal passageway 40 extending into the bottom of the outlet compartment 18.

A trough 41 is provided near the top of the unit either in the inlet chamber 16 alone, or in both the inlet chamber 16 and the intermediate chamber 17. As shown, the trough is provided in both of the chambers. This trough is formed integrally with the front wall 11, rear wall 12, side wall 13, baffle 37, and T-shaped wall members 19 and 20. The trough portion 41a extending between flanges 23 and 25 is provided with its own inner side 42, while the trough 41b is formed with its own inner side 43 extending between flanges 24 and 26. The troughs 41, 41a, and 41b

have inwardly sloping inner walls and the tops of the troughs are substantially horizontally aligned with the top of the inlet connection 36. The apertures 31 in the wall 29 of the separator are all horizontally aligned with substantially the middle portion of the troughs. All the troughs 41, 41a, and 41b are provided with downwardly and inwardly extending toothed flanges 45 constituting a continuation of the upper ends of the inner walls of the troughs and acting as strainers to catch solid particles such as paper, etc. The bottom of all the troughs is located a short distance below the lower surface of the inlet 36. As was stated before, the apertures 31, as shown, are substantially horizontally aligned with the centers of the troughs 41, 41a, and 41b. This need not be true in all cases, however, as it may sometimes be desirable to locate the apertures aligned with the upper or lower portions of the troughs.

The rear wall 12 of the unit is provided with an outlet 46 communicating with that portion of the trough 41 along the rear wall 12. The two portions of this trough that are separated by the T-shaped wall member 19 are in communication with each other by means of an aperture 47 near the bottom of the troughs. A similar aperture 48 is provided in the member 20 between those two portions of the trough adjacent the front wall 11. The outlet 46 communicates with a chamber 49, which in turn communicates with a storage chamber 50. The first chamber 49 is provided with an inverted U-shaped drain tube 52 leading to the bottom of the main body portion 10. The first chamber 49 is also provided with an inclined screen 53 beyond the drain tube 52 and extending across the chamber and from the bottom of the chamber to a point above the normal liquid level therein. The first chamber 49 is connected by a short pipe 54 with the storage chamber 50. The first chamber 49 has a removable cover 55 thereon while the storage chamber 50 has a top 56 having an opening 57 therein normally closed by a removable cover 58. In order to provide automatic means for emptying the storage chamber 50, there is provided a pump 59 that is automatically operated by float 60, floating on top of the liquid 61 within the chamber 50. The pump 59 draws liquid in through a pipe 62 extending to a point adjacent the bottom of the chamber 50 and exhausts liquid out an exhaust pipe 63.

The liquid flowing in through the inlet pipe 36 passes under the baffle 37 and into the inlet compartment 16 at a point near the bottom of the unit. Practically all of the fats, greases, and oils in the liquid will then collect at the upper portion of the compartment 16, while the solids will sink to the bottom of the unit. These solids will be carried by the flow of liquid into the intermediate chamber 17. When the liquid reaches the level in the intermediate chamber 17 of the apertures 31 in the separator 28, it will flow through these apertures into the outlet chamber 18. Any fine suspended matter flowing into the outlet chamber 18 will be stopped by the screen 32. From the outlet chamber 18, the liquid will flow through passageway 40 and passageway 39 into the outlet pipe 38.

In order to separate and carry off the lighter liquid, the troughs 41, 41a, and 41b are provided. When there is no flow of liquid into the unit, the liquid level will be substantially even with the bottoms of the apertures 31. As liquid is introduced into the unit, the liquid level will be raised to a higher operating level. The troughs 41, 41a, and 41b serve as baffle means to cause

the liquid to rise above the outlet connection 46 when liquid is flowing through the apparatus. The difference between the normal liquid level and this operating level will depend upon the size and capacity of the unit, the quantity and rate of flow of the liquid introduced thereto, and the like. The dimensions of the apertures 31 are so arranged that during operation of the separator the liquid level will be substantially near the tops of the troughs, as shown in Figs. 1 and 3. Then any oil floating on top of the liquid will flow over the top edges of the troughs into the troughs and will be carried through the outlet connection 46 into the first chamber 49. Most of the oil will be collected in the troughs at the top of the inlet chamber 16. Some, however, will be carried into the intermediate chamber 17 and will be collected in the troughs in this chamber. In many installations, however, particularly where the rate of flow is small, there will be no necessity to provide troughs in the intermediate chamber 17. Where no troughs are provided in the intermediate chamber 17, the outlet connection 46 will be arranged so that it will communicate with the troughs in the inlet chamber 16 only.

In actual operation, it will be found that the liquid 51 in the chamber 49 will ordinarily contain small amounts of water carried thereinto by the oil. This water will collect at the bottom of the chamber and may be drawn by the drain tube 52 and fed back into the bottom of the unit. The screen 53 serves to separate any small amounts of entrapped solids in the oil. The oil then flows from chamber 49 into the storage chamber 50.

As can be seen from the description of the apparatus and its operation, it is necessary that the apertures 31 be of such a size that the liquid level during operation of the apparatus will rise to the tops of the troughs. The total area of the apertures can be easily determined by those skilled in the art from the factors governing operation of the apparatus.

In the modification shown in Fig. 6, the unit 100 is similar to that shown and described in my prior United States Patents No. 1,959,623 issued May 22, 1934 and No. 2,099,061 issued November 16, 1937. The unit 100 comprises a casing 101 having a flange 102 formed integrally therewith at the upper end. The top of the casing is open and is provided with a removable grill 103 resting on the flange 102. This flange also supports a removable pan 104 which acts as a closure member for the upper end of the unit. This pan 104 is provided at one side with a horizontal slot 105 and a baffle 106. Liquid collecting in the pan 104 will flow under the baffle 106 and out of the slot 105 into the interior of the unit. The interior of the unit is provided with a pair of wall members 107 which correspond in structure and function to the walls 21 and 22 of the unit 10. A substantially U-shaped separator member 108 is disposed within the end flanges 109 of the walls 107.

The walls 107 and separator chamber 108 divide the lower portion of the unit into an inlet chamber 110 and intermediate chamber 111 and an outlet chamber 112. A removable screen 113 is positioned in the outlet chamber 112. An outlet connection 114 communicates with the interior of the outlet chamber 112.

With this arrangement any liquids which are collected in the pan 104 will flow through the slot 105 into the inlet chamber 110 through the opening 115 provided between the troughs 116 in the inlet chamber. Oil will flow over the tops of

these troughs and into the troughs and then flow through the pipe 117 into the oil chamber 118. Water in the intermediate chamber 111 will flow over the lower wall 108a into the outlet chamber 112 and out the outlet connection 114. The usual drain 119 and screen 120 is provided in the oil chamber 118 as previously described. Oil from oil chamber 118 flows through an outlet connection 121 into any type suitable storage tank.

This invention is related to those shown and described in my prior United States Patents No. 1,851,172 issued March 29, 1932 and No. 2,070,202 issued February 9, 1937.

I claim:

1. A system for separating the lightest liquid from a mixture of liquids having different specific gravities, comprising a casing having a bottom and sidewalls and having inlet and outlet connections to enable the flow of liquid therethrough, the point of communication of said outlet connection with the casing being located below the inlet connection to the casing to determine the normal liquid level in said casing, a trough positioned around the sidewalls of said casing with its upper edge a predetermined distance above said normal liquid level whereby a flow of liquid through said casing, which raises said normal liquid level above the upper edge of the trough, will result in the lightest liquid flowing into said trough, a second casing disposed exteriorly of said first casing and communicating with said trough and entraining the liquid flowing into the latter, and a drain pipe interconnecting said first casing and the lower portion of said second casing and returning to said first casing any liquid of higher specific gravity than collected from said first casing and entrained in said second casing.

2. A system for separating the lightest liquid from a mixture of liquids having different specific gravities, comprising a casing having inlet and outlet connections to enable the flow of liquid therethrough, baffle means interpositioned interiorly of said casing between said inlet and outlet connections and extending above the latter a restricted opening in the baffle means communicating the casing with the outlet, said opening being smaller than the inlet to cause liquid introduced into said casing from the inlet to flow above said outlet connection during its flow through the casing, a trough having a downwardly and inwardly extending toothed flange positioned interiorly of said casing for collecting the lightest liquid as the liquid level rises during the flow of liquid therethrough, a second casing connected with said trough for entraining said lightest liquid collected thereby, and means interconnecting said last casing and said first casing for returning any heavier liquid entrained therein to said first casing.

3. A system for separating the lightest liquid from a mixture of liquids having different specific gravities, comprising a casing having inlet and outlet connections to enable the flow of liquid therethrough, baffle means interposed interiorly of said casing between said inlet and outlet connections and extending above the latter a restricted opening in the baffle means communicating the casing with the outlet, said opening being smaller than the inlet to cause the liquid introduced into said casing from the inlet to flow above said outlet connection during its flow through the casing, a trough having a downwardly and inwardly extending toothed

flange positioned interiorly of said casing for collecting the lightest liquid as the liquid level rises during the flow of liquid therethrough, a second casing connected with said trough for entraining said lightest liquid collected thereby, means interconnecting said last casing and said first casing for returning any heavier liquid entrained therein to said first casing, and means connected with said second casing for storing said lightest liquid.

4. A system for separating the lightest liquid from a mixture of liquids having different specific gravities, comprising a casing having inlet and outlet connections to enable the flow of liquid therethrough, the point of communication of said outlet connection with the casing being located below the inlet connection to the casing to determine the normal liquid level in said casing, a trough having a downwardly and inwardly extending toothed flange positioned interiorly of said casing and formed integrally therewith with its upper portion a predetermined distance above said normal liquid level, whereby a flow of liquid through said casing, which raises the normal liquid level above the trough, will result in the lightest liquid flowing into said trough, a second casing disposed exteriorly of said first casing and communicating with said trough for entraining the liquid flowing into the latter, means connecting said second casing and the lower portion of said first casing for returning any heavier liquid entrained therein to said first casing, and means connected with said second casing for storing said lightest liquid.

5. A system of separating the lightest liquid from a mixture of liquids having different specific gravities, comprising a casing having a bottom and sidewalls and having an inlet and an outlet connected to the casing above the bottom thereof to determine a normal level of liquid in the casing and to enable the flow of liquid therethrough, a trough supported by the sidewalls and extending substantially completely therearound, said trough having an upper edge located above the normal liquid level in the casing and said trough being adapted to collect the lightest liquid as the liquid level rises in said casing due to the flow of liquid therethrough, a second casing connected with said trough for entraining said lightest liquid collected thereby, means interconnecting said second casing and said first casing for returning any heavier liquid entrained therein to said first casing, a removable screen disposed interiorly of said second casing for removing any foreign matter from the liquid passing through the same, and means connected with said second casing for storing said lightest fluid.

6. Mechanism for separating the lightest liquid from a mixture of liquids having different specific gravities, comprising a casing having a bottom and side walls and having an inlet and an outlet connected to the casing above the bottom thereof to determine a normal level of liquid in the casing and to enable the flow of liquid therethrough, a substantially U-shaped outlet chamber connected to the outlet and bisecting the casing, said chamber having a bottom spaced above the bottom of the casing to permit liquid flow thereunder from one section of the casing to the other, means connecting the outlet chamber with one of said sections, said means being located substantially level with the inlet, a trough located along the side walls in both sections and having an upper edge located above the normal liquid level for collecting the upper portion of

said liquid as the level thereof rises above the normal level due to the flow of liquid through the casing, a separating chamber having a discharge connection, means interconnecting said separating chamber with said trough to cause the liquid collected in the trough to flow into said separating chamber and a drain pipe interconnected at its ends between the lower portions of said casing and said separating chamber.
